UNITED STATES PATENT OFFICE.

MIKE KISS, OF MOLINE, ILLINOIS.

RAIL JOINT.

Application filed December 1, 1922. Serial No. 604,366.

To all whom it may concern:

Be it known that I, MIKE KISS, a citizen of the Republic of Hungary, residing at Moline, in the county of Rock Island and 5 State of Illinois, have invented new and useful Improvements in Rail Joints, of which the following is a specification.

The object of my said invention is the provision of a rail joint adapted to be expediently and easily fastened to a tie or ties and to strongly hold and embrace the adjoining portions of rails, and this without interfering with the expansion and contraction of the rails.

15 To the attainment of the foregoing, the invention consists in the improvement as hereinafter described and definitely claimed.

In the accompanying drawings, forming part of this specification:—

20 Figure 1 is a perspective showing my novel joint in use.

Figure 2 is a top plan view of the same.

Figure 3 is a cross-section taken in the plane indicated by the line 3—3 of Figure 25 2 and showing the loose connection of the interposed section to the body of the joint.

Figure 4 is an inverted plan view of the joint.

Figure 5 is a side elevation of a modification.

Figure 6 is an inverted plan view of said modification.

Similar numerals designate corresponding parts in Figures 1 to 4 to which reference 35 will first be made.

The rails 1 are preferably of the ordinary well-known construction, each including a base, a web and a head.

40 My novel joint comprises a body 2, and a section 3 in the said body 2. The said section 3 is formed of the same material as the rails 1 and corresponds in cross-section shape and size to the rails and like the rails has a base, a web and a head, as best shown in Figure 3. In the preferred embodiment 45 of my invention the section 3 is connected to the upstanding parallel portions 4 of the body 2 through the medium of an appropriate transverse connector 5; also, the section 3 and body 2 are connected by upright devices 5^x.

The joint body is preferably formed in one piece, and in addition to the said parallel upstanding portions 4 the body comprises a rail base receiving portion 6, side

ribs 7 which extend from points adjacent to the upper edges of the portions 4 to points outwardly beyond the side edges of the portion 6, and a base 8, brazed or otherwise fixed to the portion 6. The outer ends of the side ribs 7 are bifurcated as designated by 9 for the reception of spikes that fasten the joint to a tie or ties. In the embodiment shown in Figures 1 and 3 the base 8 is arranged under the portion 6 throughout the area of the latter and is provided with lateral portions 8^a and 8^b, which portions 8^a and 8^b are disposed under the extended portions of the side ribs 7 and are notched at 10 coincident with the bifurcations 9 in the said side ribs. At this point I would have it understood that when desired base sections 8^c such as shown in Figures 5 and 6 may be employed in lieu of the continuous base 8, the said sections 8^c being arranged under the ribbed portions only of the body and being separated by intervening spaces as illustrated.

It will be apparent from the foregoing that my novel joint is simple and inexpensive in construction and is susceptible of ready installation, and is adapted to strongly join the rails in such manner that a practically continuous wheel supporting surface is afforded with the gap between adjoining rails divided into two spaces.

I have entered into a detailed description of the construction and relative arrangement of the parts embraced in the present and preferred embodiments of my invention in order to impart a full, clear and exact understanding of the said embodiments. I do not desire however, to be understood as confining myself to the specific construction and relative arrangement of parts inasmuch as in the future practice of the invention various changes and modifications may be made such as fall within the scope of my invention as defined in my appended claims.

Having described my invention, what I claim and desire to secure by Letters Patent, is:—

1. The combination of the adjoining portions of two railway rails, and a joint comprising a body receiving and joining said portions, a section arranged in the body and interposed between the opposed ends of the rails; said section corresponding in cross-section to the rails and being arranged

flush therewith, and a transverse connector effecting connection of said section to the body.

2. A rail joint comprising a rail-base receiving portion, upstanding parallel portions rising from said first-named portion, transverse ribs extending from points adjacent to the upper edges of the upstanding

portions outwardly beyond the edges of the rail-base receiving portion and having bifurcations on their outer ends, and base portions arranged under the rail-base receiving portion and also arranged under the extended portions of the transverse ribs. ¹⁰

In testimony whereof I affix my signature.
MIKE KISS.
